UNITED STATES PATENT OFFICE.

AUGUST S. HELD, OF FREEPORT, ILLINOIS.

DESIGN FOR A SHELF-KEY.

SPECIFICATION forming part of **Design No. 26,771**, dated **March 16, 1897**.

Application filed December 28, 1896. Serial No. 617,268. Term of patent 14 years.

To all whom it may concern:

Be it known that I, AUGUST S. HELD, a citizen of the United States, residing at Freeport, in the county of Stephenson and State 5 of Illinois, have invented and produced a new and original Design for Supporting-Keys, of which the following is a specification, reference being had to the accompanying drawings, forming a part thereof.

10 In the drawings, Figures 1, 2, and 3 are top, bottom, and side views, respectively, of my shelf-key.

A shelf-key embodying my invention is of cylindrical form and has a spiral extending around and projecting transversely from the 15 mid-portion thereof.

What I claim is—

The design for a shelf-key herein shown and described.

AUGUST S. HELD.
